UNITED STATES PATENT OFFICE.

ELIJAH P. HARRIS, OF CHICAGO, ILLINOIS, ASSIGNEE TO THE PAYSON MANUFACTURING COMPANY, OF CHICAGO, ILLINOIS, A CORPORATION OF ILLINOIS.

SASH-OPERATING DEVICE.

1,056,738.

Specification of Letters Patent. Patented Mar. 25, 1913.

Application filed August 15, 1912. Serial No. 715,206.

To all whom it may concern:

Be it known that I, ELIJAH PREBLE HARRIS, citizen of the United States, residing at Chicago, in the county of Cook and State of Illinois, have invented a certain new and useful Improvement in Sash-Operating Devices, of which the following is a full, clear, concise, and exact description.

My invention relates to sash operating devices and more particularly to means for opening and closing continuous, hinged steel-sashes. Its object is to provide means whereby in opening or closing the sash, a direct outward push or inward pull is exerted upon the sash, thereby preventing any lateral strain being exerted upon the sash.

In factory buildings or the like it is common to provide a steel sash extending continuously across the side or roof of a building or of a considerable portion thereof, such sash section being hinged at the upper edge thereof or otherwise suitably pivoted and adapted to be swung outwardly at the bottom for purposes of ventilation. For operating such sash section it is common to provide a rod extending the length of the section, means being provided for imparting longitudinal movement to the rod, and means also being provided for operatively connecting said rod with the hinged sash. The thrust for opening and closing the sash being thus initially applied laterally of the sash, there has been considerable difficulty in providing means for opening the sash with a straight outward thrust, the tendency being to give the sash a slight lateral or end motion which causes the sash to bind or rub against the end of the frame in which the sash fits.

My invention is designed to provide means for operatively connecting the traveler rod with the swinging sash in such manner that the longitudinal travel of the rod exerts a straight outward pull or push upon the window sash.

My invention contemplates a rectangular system of levers, which in effect provides, in a single system of levers, two complementary lazy-tongs which operate at right angles to each other, two of the members of one of the lazy-tongs being continuations of two of the members of the other lazy-tongs. Thus the operation of one set of lazy-tongs by the vertical rod causes the complementary actuation of the other set of lazy-tongs and

produces a straight outward pull or push upon the sash.

My invention may be more readily understood by reference to the accompanying drawings, in which—

Figure 1 is a plan view of a sash operating device in position for holding the sash closed, the sash being shown in horizontal section; Fig. 2 is a similar view showing the device in position for holding the sash open; Fig. 3 is an enlarged view as seen from the line 3—3 of Fig. 2; and Fig. 4 is an enlarged, front view of one end of the window sash showing one only of the sash operating devices.

Similar letters of reference refer to similar parts throughout the several views.

The continuous sash 1 may be hinged at its top to swing outwardly in the usual manner. In its closed position the sash 1 fits the frame 2. Suitably supported, and extending in a direction parallel with the length or width of the sash, is a traveler-rod 3 which may be of the usual construction and mounted in the usual manner. For purposes of illustration I have shown the rod 3 threaded at one end, as at 4, and extending through a threaded pulley 5, whereby the rotation of the pulley will cause a longitudinal travel of the rod 3. Throughout its length the rod 3 is supported by brackets 6 provided with rollers 7 for supporting the rod 3. This means of supporting and operating the traveler rod forms no part of my present invention and any other suitable means may be substituted therefor.

The means for operatively connecting the rod 3 with the sash 1 comprises a rectangular system of levers composed of two parallel side levers 8, 9 and two parallel end levers 10, 11 pivotally connected at their ends. The middle points of the side levers 8 and 9 are also connected by an intermediate lever 18 pivoted at its ends to said middle point of the levers 8 and 9, respectively. The middle point of the lever 8 is pivotally mounted upon the bracket 6. This is preferably done by providing an upward extension 13 of the bracket 6, such extension being provided with an eye through which the pin 12 passes, thus permitting of a slight rocking of the pivot 12 in its socket.

To the corner at which the levers 9 and 10 are pivoted together, as by a pin 17, there is clamped an extension 14, the end of which

is pivoted at 15 to a bracket 16 mounted upon the lower edge of the window sash. The brackets 6 and 16 are so located with respect to each other that the pins 17 and 12 5 are in a plane perpendicular to the rod 3.

It will be noted that the levers 10 and 18 and the ends of the levers 8 and 9 constitute a lazy-tong structure, one end of which is pivoted to the window sash and the other 10 end to the bracket which supports the traveler rod. Such lazy-tong structure will in its operation produce a straight push or pull upon the window sash. In order to produce such operation of said lazy-tongs I 15 provide another set of lazy-tongs, two of the elements of which comprise the other ends of the levers 8 and 9. Another element of said last mentioned lazy-tongs consists of the intermediate lever 18, and the fourth 20 element thereof consists of the end lever 11 which connects the ends of the parallel side levers 8 and 9. The corner at which the rods 9 and 11 are connected by the pin 19 is secured to the traveler rod 3. This is pref- 25 erably done by clamping to said rod 3 a bracket 20, the upper end of which is formed with a socket for receiving the pin 19. Thus the second set of lazy-tongs operates in a direction perpendicular to the direction of 30 operation of said first mentioned set of lazy-tongs. That is, when the traveler-rod 3 is moved so as to bring the corners 19 and 12 of one set of lazy-tongs closer together as 35 shown in Fig. 2, the other set of lazy-tongs is extended. It thus appears that for opera- 40 tively connecting the traveler-rod to the sash, my invention, in its preferred embodiment, provides in effect two sets of lazy-tongs having complementary operation and 45 comprises a unitary structure consisting of two parallel side levers 8 and 9, and two parallel end levers 10 and 11 pivoted together at their ends, the side levers 8 and 9 being connected at their middle points by an 50 intermediate lever 18 pivoted at its ends to said levers. The middle point of the lever 8 is the fixed end of each of the two complementary lazy-tongs and is pivotally mounted upon a bracket, the pivotal point

of said lever being in vertical alinement with 50 the traveler-rod 3. The other ends of the two lazy-tongs are secured to the hinged sash and the traveler-rod, respectively.

What I claim is:

1. The combination with a hinged sash; 55 of an operating-rod extending parallel thereto; means for imparting longitudinal motion to said operating rod; and a rectangular system of levers interconnecting said sash and rod, comprising two side levers 60 and two end levers pivoted together, the corners of the rectangle at the opposite ends of one of said side levers being pivotally secured to said sash and said rod, respectively; and a fixed support to which the 65 middle point of said other side lever is pivotally secured.

2. The combination with a hinged sash; 70 of an operating-rod extending parallel thereto; means for imparting longitudinal motion to said operating rod; and a rectangular system of levers interconnecting said sash and rod, comprising two side levers and two 75 end levers pivoted together, and an intermediate lever pivoted at its ends to the middle points of said side levers, the corners of the rectangle at the opposite ends of one of said side levers being pivotally secured to said sash and said rod, respectively; and a fixed support to which the middle point of 80 said other side lever is pivotally secured.

3. The combination with a hinged sash; 85 of an operating-rod extending parallel thereto; means for imparting longitudinal motion to said operating rod; and means for opera- 90 tively connecting said rod and said sash, said means comprising a unitary structure consisting of two complementary acting sets of lazy-tongs having a common fixed pivotal point and having their movable ends pivot- 95 ally secured to said sash and said traveler rod respectively.

In witness whereof, I, hereunto subscribe my name this 30th day of July, A. D., 1912.

E. P. HARRIS.
